LIQUID DISPENSER

Smith Kyser, 4820 Kyser Road, Lowell, Mich., assignor to Mazurflo Corporation, Saranac, Mich., a corporation of Michigan

Filed Mar. 16, 1961, Ser. No. 64,344

Term of patent 14 years

(Cl. D58—26)

FIGURE 2 is a side perspective view of the opposite side thereof showing my design as it appears when in use with parts of the tube being shown broken away for convenience of illustration. The broken line showing of the can is for illustrative purposes only.

I claim:

The ornamental design for a liquid dispenser, as shown and described.
